Filed Dec. 3, 1954, Ser. No. 472,925

13 Claims. (Cl. 315—3.5)

This invention relates to traveling wave electron discharge devices and more particularly to transition arrangements for matching a low impedance waveguide to the relatively high impedance waveguiding structure usually employed in such devices.

In the copending applications of J. H. Bryant, Serial No. 312,155, filed September 29, 1952, now U.S. Patent No. 2,794,145, R. E. White, Serial No. 312,083, filed September 29, 1952 now U.S. Patent No. 2,794,144, and R. E. White et al., Serial No. 471,412, filed November 26, 1954, now abandoned, certain forms of transition arrangements are disclosed which provide for impedance matching between the end of the high impedance helical transmission line and the relatively low impedance radio frequency terminal connections of a traveling wave electron discharge device or tube. In the aforesaid copending applications, the transition arrangements are disposed transversely of the axis of the helix and made in such form as to require but a small fraction of an inch of space measured in an axial direction. These matching arrangements thus reserve substantially all the available space between the source of electron beam supply and the electron collector for the helical line.

The impedance matching arrangements of the first two copending applications include parallel transmission line sections, the lengths of which are frequency dependent while the latter copending application includes a series transmission line section, the radial dimension of which is frequency dependent. The traveling wave tubes employing these impedance matching arrangements will have a diameter dependent upon the frequency at which the tube is operating and in certain instances this diameter may be quite large.

It is one of the objects of this invention to provide still another form of transition arrangement which also requires very little axial space and which will enable the diameter of a traveling wave tube to be substantially smaller than a traveling wave tube employing the previous transition arrangements.

Another object is to provide transition sections for precise matching of a low impedance radio frequency coaxial terminal connection to a high impedance helical line.

One of the features of this invention is the structural arrangement of the transition section, that is, the special shaping of certain of the conductors thereof so as to provide gradual transition from the size of the outer conductor of the coaxial terminal connection to the smaller conductor size of a helical line and for cooperation in the impedance matching function. This is accomplished by tapering the width of the transition section.

Another feature of this invention is the provision of a specially designed strip conductor in conjunction with a cylindrical conductor for transmission of radio fre-

2

quency energy between the terminal connections and the helical line by providing the strip conductor in the form of a spiral spaced from the cylindrical conductor by a dielectric medium, the spacing therebetween being radially tapered between the point of coupling with the terminal connection and the helical line for cooperation in matching the impedances of said connection and said helical line.

Still another feature of this invention is the provision of a spiral strip conductor in conjunction with a cylindrical conducting surface wherein the strip conductor and the cylindrical conducting surface are coupled together at one point to establish a radio frequency voltage null, said coupling together being capacitive in nature and the point of coupling being variable along a given arc of the cylindrical conducting surface to enable the selection of a predetermined frequency of operation within a given range of operating frequencies for a traveling wave tube.

20 The above-mentioned and other features and objects of this invention will become more apparent by reference to the following description taken in conjunction with the accompanying drawings, in which:

Fig. 1 is a fragmentary view in longitudinal section of a traveling wave electron tube incorporated in transition sections at the ends of a helical line in accordance with the principles of this invention;

Fig. 2 is a cross-sectional view of the transition section of this invention taken along line 2—2 of Fig. 1; and

30 Fig. 3 is a cross-sectional view of an alternative embodiment of the transition section of this invention.

Referring to Fig. 1 of the drawing, a longitudinal section of the pertinent parts of a traveling wave electron discharge device is shown together with an illustration

35 of an embodiment of the present invention. The tube generally comprises an electron gun unit 1 for producing a beam of electrons for flow axially of the tube to a collector 2. The electron gun unit is either spaced from or made contiguous to an alignment or partition plate

40 3 which is positioned crosswise vacuum envelope 4 against abutment 5 on the inner surface thereof. Envelope 4 preferably is composed of a non-magnetic metallic material in the embodiment presently being discussed, but it is to be understood that the vacuum envelope may be 45 composed of dielectric material which has disposed concentrically therewith a non-magnetic metallic cylinder as disclosed in the cross-sectional view of Fig. 3. Carried on the outer surface of the envelope 4 of the cylinder shell 6 of Fig. 3 is either a permanent magnet or magnetic coil 7 which serves to produce a magnetic field 50 axially of the envelope 4. At the rear of the envelope is a second alignment or partition plate 8. Interposed between these two plates 3 and 8 is a radio frequency propagating structure 9 in the form of a helical transmission line, the line being supported by dielectric rods 55 10 or by a dielectric tube, whichever is desired. Any suitable dielectric, such as glass or quartz may be employed. The rods or tubing are supported on the plates 3 and 8 in openings 11 and 12. The helical line 9 is 60 connected between the input and output radio frequency terminal connections 13 and 14 by means of transition arrangements or sections 15 and 16, respectively.

The transition section 15, for example, comprises a transmission line arrangement of the line-above-ground type which includes the envelope 4 as one of the conductors and a strip conductor 17 as the other conductor wherein conductor 4 provides a reference or ground plane separated from the strip conductor 17 by a suitable dielec-

tric medium shown herein to be vacuum but may comprise a solid dielectric such as a suitable ceramic material. As disclosed in Fig. 2, the conductor 4 presents a cylindrical conducting surface 18 to the spiral shaped strip conductor 17 which is shorted directly thereto at point 19 with the other end thereof connected or otherwise coupled to the helical line 9. By making the strip conductor equal approximately to a quarter wavelength long or an odd multiple thereof over the operating frequency range of the traveling wave tube, the section 15 becomes resonant and thereby establishes a standing wave with a voltage null at the short 19 and a voltage maximum at the end coupled to the helical line 9. The outer conductor 20 of the input radio frequency terminal connection 13 is connected to envelope 4 and the inner conductor 21 is connected to the strip conductor 17. The connection between inner conductor 21 and strip 17 may be provided by a conductor 22 brazed or otherwise bonded to conductor 17 and projecting through an aperture in envelope 4 which makes electrical contact with inner conductor 21 by means of socket 23. The aperture through which conductor 22 passes through envelope 4 is sealed for vacuum purposes by the dielectric seal 24. The connection to strip conductor 17 is located at a point between the voltage null (minimum impedance) and the voltage maximum (maximum impedance) points so as to provide a proper impedance match between the high impedance helical line 9 and the low impedance coaxial connection 13. In order to provide a gradual transition and thereby avoid discontinuities to flow of radio frequency energy between the width of the strip 17 at the connection to the coaxial line 13 and the size of the helical conductor, the strip is tapered as indicated at 25.

The transition coupling 15 in Figs. 1 and 2 provides for the propagation of radio frequency energy from the coaxial connection 13 to the helical line 9 by means of a concentric-like strip-above-ground type transmission line comprising the spiral strip 17 and the cylindrical conductor surface of envelope 4. The transition section 16 is identical to the form shown in 15, the propagation, however, being in the reverse direction of the transition section.

The strip conductor 17 spaced a small fraction of a quarter wavelength from the cylindrical conducting surface of the envelope 4 provides for the propagation of electromagnetic waves from the coaxial connection 13 in a mode approximating the TEM mode. The strip 17 is preferably of a width sufficient to provide satisfactory coupling to the coaxial transmission line, the portion disposed between this coupling and the helical line being tapered as indicated at 25 to provide a gradual transition down to the size of the helical conductor and also to cooperate in the impedance transition between helical line 9 and connection 13. The dimension h for the strip 17 over the cylindrical conducting surface of envelope 4 may be obtained from the expression

$$Z_0 \approx \frac{377h}{\epsilon d} \left(1 - \frac{2h}{\pi d} \ln \frac{\pi d}{2h}\right)$$

where h is the spacing of the strip from the cylindrical surface, d is the width of the strip 17 and ϵ is the dielectric constant of the dielectric material disposed between the strip and the cylindrical surface. As will be obvious from the above expression, if the dimension h is varied between the point of contact with the connection 13, and the connection to helix 9, there has then been introduced another variable which cooperates in the desired impedance match.

Fig. 2 illustrates the variation between strip 17 and envelope 4 to achieve this added variable by making strip 17 substantially spiral in nature from the connection to coaxial line 13 and the helical line 9. Conforming strip 17 in the form of a spiral provides a radial tapering be-

tween the strip conductor 17 and the cylindrical conducting surface of envelope 4.

A pointed out hereinabove, the tapering of the width of strip 17 enables a transition between the size of the center conductor 21 of connection 13 and the size of the conductor forming helical line 9 and also cooperates in the desired impedance match. This tapering of the width of strip 17 as indicated at 25 also aids in obtaining a wide bandwidth in the transition section 15, the bandwidth 10 of which should be as large as the bandwidth of the remaining portions of the traveling wave tube.

In the aforementioned copending applications, there was disposed about the transition sections a shielding arrangement to eliminate any radiation which may occur 15 from the transmission section and which might interfere in the desired operation of the traveling wave tube. The radiation problem when employing a transition arrangement of the type herein described is substantially eliminated by dimensioning the envelope 4 to have a diameter 20 of such a value that this envelope or outer cylinder functions as a waveguide beyond cut-off for the operating frequency of the device. If this is done, radiation in either direction from the transition arrangement is eliminated. By employing this cylinder as the envelope 4 as 25 hereinabove proposed, the overall diameter of the traveling wave tube may be substantially decreased. Likewise, by employing the coaxial vacuum seal 24 of Fig. 1, the number of parts in the vacuum envelope can be decreased 30 which is desirable for increased efficiency in the outgassing of electron discharge devices.

Referring to Fig. 3, an alternative embodiment of the transition arrangement of this invention is illustrated. Employing this embodiment will enable a selection of a predetermined frequency of operation for the traveling 35 wave tube within a given operating frequency range. As mentioned hereinabove with respect to Fig. 1, the envelope 4 thereof could be ceramic rather than metallic. Thus, in Fig. 3, it is proposed that envelope 4a be formed from a suitable dielectric material, such as quartz or glass, 40 which has disposed thereabout in a concentric relation conductive cylinder 6 to function as the ground plane of the concentric-like strip-above-ground type transmission line for utilization in the transition arrangement of this invention. Strip conductor 17a is coupled to conducting 45 cylinder 6 capacitively to provide a resonant transition section as disclosed in connection with Figs. 1 and 2. Portion 26 of strip conductor 17a effectively is one plate of a capacitor while sliding element 27 forms the other plate of a capacitor with the dielectric material of envelope 50 4a functioning as the dielectric material disposed therebetween. This structure arrangement provides a capacitive short for radio frequency waves between cylinder 6 and strip 17a. Sliding element 27 is in slidable contact with a portion of cylinder 6 over a smaller arc thereof. 55 Element 27 may be moved by handle 28 in slot 29 to change the location of the short or coupling between strip 17a and cylinder 6 such that the resonant length of strip 17a may be varied over a small range to enable 60 the selection of a particular frequency of operation with respect thereto.

The arc through which sliding element 27 may be 65 moved, and thereby the range of frequency selection, is determined by the length of element 27 and slot 29. This comes about by the fact that if slot 29 is not covered by sliding element 27 a radiation through slot 29 will occur. Thus, the slot 29 must be covered at all times and in all 70 positions of element 27 by element 27 to prevent undesired radiation from the traveling wave tube through slot 29. This radiation consideration, therefore, restricts the number of frequencies which may be selected from a given range of operating frequencies.

75 While I have described above the principles of my in-

vention in connection with specific apparatus, it is to be clearly understood that this description is made only by way of example and not as a limitation to the scope of my invention as set forth in the objects thereof and in the accompanying claims.

I claim:

1. In a traveling wave electron discharge device having a radio frequency wave propagating structure of relatively high characteristic impedance and a radio frequency transmission line of relatively low characteristic impedance; a transition section coupling said low impedance line to said propagating structure comprising a first conductor substantially concentric with the longitudinal axis of said propagating structure, a second conductor spaced radially from said first conductor having a substantially spiral-like configuration about said longitudinal axis, said first and second conductors forming a transmission line spaced radially from and disposed about an end of said propagating structure, means coupling said first and second conductors together at one point to establish a radio frequency voltage null, the length of said transmission line from said voltage null measured circumferentially therealong providing a resonant section resonant at approximately the operating frequency of said device, said transmission line having a high radio frequency voltage portion disposed adjacent said propagating structure, means connecting said high voltage portion to said propagating structure, and means to couple said low impedance line to said first and second conductors at a point between said voltage null and said high voltage portion to match the impedance of said low impedance line.

2. In a traveling wave electron discharge device having a radio frequency wave propagating structure of relatively high characteristic impedance and a radio frequency transmission line of relatively low characteristic impedance; a transition section coupling said low impedance line to said propagating structure comprising a first conductor substantially concentric with the longitudinal axis of said propagating structure, a second conductor spaced radially from said first conductor having a substantially spiral-like configuration about said longitudinal axis, said first and second conductors forming a transmission line spaced radially from and disposed about an end of said propagating structure, means coupling said first and second conductors together at one point to establish a radio frequency voltage null, the length of said transmission line from said voltage null measured circumferentially therealong providing a resonant section resonant at approximately the operating frequency of said device, said transmission line having a high radio frequency voltage portion disposed adjacent said propagating structure, means connecting said high voltage portion to said propagating structure, means to couple said low impedance line to said first and second conductors at a point between said voltage null and said high voltage portion to match the impedance of said low impedance line, and said second conductor being tapered from the point of coupling to said low impedance line to the point of connection to said propagating structure.

3. In a traveling wave electron discharge device having a radio frequency wave propagating structure of relatively high characteristic impedance and a radio frequency transmission line of relatively low characteristic impedance; a transition section coupling said low impedance line to said propagating structure comprising a first conductor substantially concentric with the longitudinal axis of said propagating structure, a second conductor spaced radially from said first conductor having a substantially spiral-like configuration about said longitudinal axis, said first and second conductors forming a transmission line spaced radially from and disposed about one end of said propagating structure, capacitive means coupling said first and second conductors together at one point to establish a radio frequency voltage null, the

length of said transmission line from said voltage null measured circumferentially therealong providing a resonant section resonant at approximately the operating frequency of said device, said transmission line having a high ratio frequency voltage portion disposed adjacent said propagating structure, means connecting said high voltage portion to said propagating structure, and means to couple said low impedance line to said first and second conductors at a point between said voltage null and said high voltage portion to match the impedance of said low impedance line.

4. In a traveling wave electron discharge device having a helical propagating structure of relatively high characteristic impedance and a radio frequency transmission line for launching the radiation into the structure, the

15 line of relatively low characteristic impedance; a transition section coupling said low impedance line to said helical structure comprising a cylindrical conducting surface substantially concentric with the longitudinal axis of said helical structure, a strip conductor spaced radially

20 from said surface having a substantially spiral-like configuration about said longitudinal axis, said surface and said strip forming a transmission line spaced radially from and disposed about an end of said helical structure, means coupling said surface and said strip together at

25 one point to establish a radio frequency voltage null, the length of said transmission line from said voltage null measured circumferentially therealong providing a resonant section resonant at approximately the operating frequency of said device, said transmission line providing a

30 voltage maximum point at a distance of approximately a quarter wavelength of said operating frequency from said null point, means coupling said low impedance line to said surface and said strip at a point between said null and said maximum point to match the impedance of said

35 low impedance line, means to connect said strip in the region of said voltage maximum point to said helical structure, said strip being tapered from the point of coupling to said low impedance line to the point of coupling to said helical structure.

40 5. A transition coupler for use between a low impedance transmission line and a high impedance transmission line comprising a first conductor substantially concentric with a given axis, a second conductor spaced radially from said first conductor having a substantially spiral-like configuration about said given axis, said first and second

45 conductors forming a transmission line, means coupling said first and second conductors together at one point to establish an impedance minimum, the length of said transmission line from said impedance minimum measured circumferentially therealong providing a resonant section

50. Unsymmetrically increasing providing a resonant section resonant at a given frequency, said transmission line having an impedance maximum point at a distance approximately one quarter wavelength of said given frequency from said impedance minimum point, means coupling said low impedance line to said first and second conductors.

55 said low impedance line to said first and second conductors at a point between said minimum and maximum impedance points, and means to connect said second conductor in the zone of said maximum impedance to said high impedance line.

6. A transition coupler for use between a low impedance transmission line and a high impedance transmission line comprising a first conductor substantially concentric with a given axis, a second conductor spaced radially from said first conductor having a substantially spiral-like configuration about said given axis, said first and

like configuration about said given axis, said first and
65 second conductors forming a transmission line, means
coupling said first and second conductors together at one
point to establish an impedance minimum point, the
length of said transmission line from said impedance
minimum point measured circumferentially therealong
70 providing a resonant section resonant at a given fre-
quency, said transmission line having an impedance max-
imum point at a distance of approximately one quarter
wavelength of said given frequency from said minimum
point, means coupling said low impedance line to said
75 first and second conductors at a point between said im-

pedance minimum and impedance maximum points to match the impedance of said low impedance line, means connecting said second conductor in the region of said impedance maximum point to said high impedance line, and said second conductor being tapered from the point of coupling to said low impedance line to the point of coupling to said high impedance line.

7. A transition coupler for use between a low impedance transmission line and a high impedance transmission line comprising a first conductor substantially concentric with a given axis, a second conductor spaced radially from said first conductor having a substantially spiral-like configuration about said given axis, said first and second conductors forming a transmission line, means coupling said first and second conductors together at a point to establish an impedance minimum point, the length of said transmission line from said impedance minimum point measured circumferentially therealong providing a resonant section resonant at a given frequency, said transmission line having an impedance maximum point at a distance approximately one quarter wavelength of said given frequency from said impedance minimum point, means coupling said low impedance line to said conductors at a point between said impedance minimum and impedance maximum points, means connecting said second conductor in the region of said impedance maximum impedance point to said high impedance line, and said first conductor has a diameter of appropriate value to impart to said first conductor the characteristic of a waveguide beyond cutoff for said given frequency.

8. A transition coupler for impedance matching between a low impedance transmission line and a high impedance transmission line comprising a cylindrical conducting surface substantially concentric to a given axis, a strip conductor spaced radially from said surface having a substantially spiral-like configuration about said given axis, said conducting surface and said strip conductor forming a transmission line, means coupling said conducting surface and said strip conductor together at one point to establish an impedance minimum point, the length of said transmission line from said impedance minimum point measured circumferentially therealong providing a resonant section resonant at a given frequency, said transmission line having an impedance maximum point at a distance of approximately one quarter wavelength of said given frequency from said impedance minimum point, means coupling said low impedance line to said surface and said strip at a point between said impedance minimum and impedance maximum points to match the impedance of said low impedance line, and means connecting said strip in the region of said maximum impedance point to said high impedance line.

9. A transition coupler for impedance matching between a low impedance transmission line and a high impedance transmission line comprising a cylindrical conducting surface substantially concentric to a given axis, a strip conductor spaced radially from said surface having a substantially spiral-like configuration about said given axis, said conducting surface and said strip conductor forming a transmission line, capacitive means coupling said surface and said strip together at one point to establish an impedance minimum point, the length of said transmission line from said impedance minimum point measured circumferentially therealong providing a resonant section resonant at a given frequency, said transmission line having an impedance maximum point at a distance of approximately one quarter wavelength of said given frequency from said impedance minimum point, the impedance of said transmission line steadily increasing between said impedance minimum point to said impedance maximum point, means coupling said low impedance line to said surface and said strip conductor at a given point between said impedance minimum and impedance maximum points to match the impedance of said low impedance line, and means connecting said strip in

the region of said impedance maximum point to said high impedance line.

10. A traveling wave electron discharge device comprising a metallic envelope, means to project an electron beam along a path axially of said envelope, a radio frequency wave propagating structure of relatively high characteristic impedance disposed coaxially of said path, a radio frequency wave input terminal connection of relatively low characteristic impedance, a radio frequency wave output terminal connection of relatively low characteristic impedance, a transition section coupling said input connection to the end of said propagating structure adjacent said means to project for the propagation of radio frequency wave therealong for interaction with the electrons of said beam, and a transition section coupling said output connection to the other end of said propagating structure for removal of the interacted radio frequency wave therefrom, each of said transition sections including said envelope and a conductor spaced radially from said envelope having a substantially spiral-like configuration about the axis of said envelope, said envelope and said conductor forming a transmission line spaced radially from and disposed about the respective end of said propagating structure, means coupling said envelope and said conductor together at one point to establish a radio frequency voltage null, the length of said transmission line from said voltage null measured circumferentially therealong providing a resonant section resonant at approximately the operating frequency of said device, said transmission line having a high radio frequency voltage portion disposed adjacent said propagating structure, means connecting said high voltage portion to said propagating structure, and means to couple said terminal connection to said envelope and said conductor at a point between said voltage null and said high voltage portion to match the impedance of said terminal connection.

11. A device according to claim 10, wherein the diameter of said envelope is such as to establish said envelope as a waveguide beyond cutoff for the operating frequency of said device and the inner surface of said envelope defines a cylindrical conductive surface and said conductor includes a strip of conducting material separated from said cylindrical conducting surface by a dielectric medium.

12. A device according to claim 11, wherein said strip includes a portion tapered from the point of coupling to said terminal connection and the point of connection to said propagating structure.

13. A traveling wave electron discharge device comprising a vacuum envelope of dielectric material, means to project an electron beam along a path axially of said envelope, a helical radio frequency wave propagating structure of relatively high characteristic impedance disposed coaxially of said path, a radio frequency wave input terminal connection of relatively low characteristic impedance, a radio frequency wave output terminal connection of relatively low characteristic impedance, a transition section coupling said input connection to the end of said helical structure adjacent said means to project for launching radio frequency waves on said helical structure for interaction with the electrons of said beam, a transition section coupling said output connection to the other end of said helical structure for removal of the interacted radio frequency wave therefrom, and a metallic sleeve disposed in concentric spaced relation to said envelope, each of said transition sections including said sleeve and a conductor spaced radially from said sleeve having a substantially spiral-like configuration about the axis of said envelope, said sleeve and said conductor forming a transmission line spaced radially from and disposed about respective ends of said propagating structure, movable means disposed adjacent said envelope to capacitively couple together said conductor and said sleeve at one point to establish a radio frequency voltage null, the length of said transmission line from said

voltage null measured circumferentially therealong being adjusted by the positioning of said movable means to provide a resonant section at a selected frequency in the operating frequency range of said device, said transmission line having a high radio frequency voltage portion disposed adjacent said propagating structure, means connecting said high voltage portion to said propagating structure, and means to couple said terminal connections to said conductor and said sleeve at a point between said

voltage null and said high voltage portion to match the impedance of said terminal connections.
